UNITED STATES PATENT OFFICE.

JOHN C. KOPE, OF BELLEVUE BOROUGH, PENNSYLVANIA, ASSIGNOR TO THE DUFF MANUFACTURING COMPANY, OF PITTSBURGH, PENNSYLVANIA, A CORPORATION OF PENNSYLVANIA.

JACK.

1,837,519.

Specification of Letters Patent. Patented Apr. 20, 1920.

Application filed October 24, 1919. Serial No. 832,867.

To all whom it may concern:

Be it known that I, JOHN C. KOPE, a citizen of the United States, and resident of the borough of Bellevue, in the county of Allegheny and State of Pennsylvania, have invented a new and useful Jack, of which the following is a specification.

The invention relates to jacks or the like, and has for its object to provide a jack which shall be comparatively simple, light, compact, efficient, and easy to produce. Specifically the present invention is an improvement or modification upon and within the kind of jack disclosed in my Patent No. 1,317,878, dated October 7, 1919, wherein a double rack with twin pinions are operated by a double conical or convex spiral pinion meshing between a pair of buttress-toothed gears, the working faces of the spiral pinion having a major spiral pitch and a minor helical pitch and exerting power through line contact upon series of teeth on the converging arcs of the buttress gears, substantially at right angles to the axis of rotation of the pinion. In the particular embodiment illustrated in said patent, the double spiral pinion is operated directly by a reciprocating ratchet-handle on its shaft. In the construction herein disclosed the double spiral pinion has a central gear portion, which is driven by a pinion on a central upwardly inclined axis. This affords a further multiplication of power, permits an increase in the diameter of the rack pinions and a decrease in the size of the buttress gears, with corresponding alteration in the frame and casing, whereby greater lightness and compactness are secured, and makes possible certain economies in manufacture. Furthermore the advantage of distance operation without stooping, by a long rotary handle, is secured.

In the accompanying drawings, forming a part hereof:

Figure 1 is a side elevation of the jack, with the intermediate portion of its handle broken away for economy of space;

Fig. 2 is a central vertical section in a fore and aft plane;

Fig. 3 is a front elevation with the cover removed, and the double spiral pinion member in section;

Fig. 4 is a horizontal cross-section on the line 4—4 of Fig. 2;

Fig. 5 is a horizontal cross-section on the line 5—5 of Fig. 2;

Fig. 6 is a horizontal section showing a modification; and

Fig. 7 is an elevation of a portion of the round neck of Fig. 6.

The device has a frame or stand 1, with a suitable base 2. In the stand is a vertical guide chamber 3 for a rack-bar 4, having a head 4^a and if desired a depending external toe-lift 5. The opposite sides of this rack-bar are preferably channelled, and in these channels are the rack teeth 6.

In rear pinion chambers 7 in the upper part of the stand twin pinions 8 mesh with the recessed sides of the rack. Said rack-pinions are mounted on parallel shafts 9 at opposite sides of the rack, journaled in fixed front and rear bearings 10 and 11 in the frame, the front bearings being supported by suitable walls or webs 12 between the rack-pinion chambers and a front chamber 13, which is provided with a front cover 14 detachably secured by screws 15.

Fast on the forward ends of said shafts within the chamber 13 are gears 16 having 80 reversely disposed straight buttress teeth 17, that is to say, triangular teeth the backs of which are sloped, and the working faces approximately perpendicular and parallel with the axis from front to back. Said 85 gears are meshed simultaneously by a double spiral pinion 18, comprising a disk mounted on a transverse axis below the gears and having convex or broadly conical sides projecting upward between the lower, converging arcs of the gears. Said sides are formed each with a spiral working face 19, having a constantly varying major spiral or radial pitch, a constantly varying minor helical pitch, and a constantly varying angle, 90 whereby in lifting the pinion acts with line contact upon two or more teeth on each gear in the upward direction, substantially at right angles to the transverse axis of the pinion, all as set forth more particularly in 100 my patent aforesaid.

The double spiral pinion 18 is supported loosely upon the center of a transverse idle shaft 20, which is mounted loosely in closed, laterally-spaced journal bearings 21 carried 105 by the internal walls of the body of the stand. In assembling, said shaft is inserted endwise through the bearings and pinion,

and when in place is held against coming out by the side flanges 22 of the cover 14 opposed to its ends, as seen in Fig. 4.

The double pinion 18 of the present invention is a compound, integral gear-member, comprising, in addition to the lateral spiral pinion portions, a central gear portion, consisting of worm gear teeth 23 cut on the periphery of the member in position to clear the teeth of the buttress-gears.

Said gear is meshed by a worm or driving pinion 24 below the member 18, the axis of this pinion lying substantially in the central plane normal to the transverse axis of the compound double-pinion and gear member, and being inclined upwardly and forwardly. The rear, lower journal or shaft end 25 of said worm is rotatably supported in a bearing 26 in the body of the stand, and its upper, forward journal 27 is similarly supported in a bonnet bearing 28 in the cover 14. A projecting shaft end 29 is provided with a cross-pin 30, whereby it is adapted to receive the slotted socket end 31 of a removable long rotary crank handle 32, by means of which the jack can be operated by a person in a standing position.

The pinion 24 and gear 23 constitute a multiplying driving means for the double spiral pinion, which as heretofore stated makes it possible to increase the size of the rack-pinions 8 and decrease that of the buttress-gears 16. From this a smaller and less projecting inclosure at the upper end of the standard results; and the application of external power through the rotary handle at a lower, central region also makes for compactness and greater stability. The reaction of the worm 24 and worm gear teeth 23 produces some lateral or axial thrust upon the double spiral pinion member 18, which is taken up by the confinement of the member between the bearings 21.

The projection of the rack-pinions 8 into the channeled toothed sides of the rack-bar 4 contributes to the lateral compactness of the organization. It is also possible to construct and assemble said pinions in an inexpensive manner by making them of a plurality of separate punched-out laminations 33 which are held together simply by being strung on angular or keying portions 34 of the shafts 9, between shoulders 35 on said shafts and side-bearings 36 on the back of the frame. At the working regions, the teeth of the laminated pinions are confined by the side flanges 37 of the rack channels. The thin toothed disks composing the pinions are introduced into the pinion chambers by way of the rack channel 3, through an opening 38 from the front chamber 13.

From the foregoing and in connection with my prior patent, the operation of the device will be readily understood. While the preferred embodiment has been de-

scribed in detail, it will be understood that numerous changes may be made without departing from the matters of novelty herein contained.

Figs. 6 and 7 illustrate the fact that a round rack 4^b having teeth 6^a extending circumferentially around it may be employed. Such rack is free to turn, presenting fresh portions of its teeth to the engagement of the pinions 8, whereby the life of the rack is prolonged.

What I claim as new is:

1. A jack comprising a frame, a double rack-bar therein, pinions meshing the rack-bar at opposite sides, a pair of gears connected with the rack-pinions and having buttress teeth reversely disposed, a double spiral pinion on a transverse axis projecting in meshing engagement between said buttress gears, the working faces of the spiral pinion having a major spiral pitch and a minor helical pitch and adapted to exert power upon series of teeth on the converging arcs of the buttress gears substantially at right angles to the transverse axis, in combination with a gear on the middle of said double spiral pinion, and a driving pinion meshing with said gear.

2. A jack comprising a frame, a double rack-bar therein, pinions meshing the rack-bar at opposite sides, a pair of gears connected with the rack-pinions and having buttress teeth reversely disposed, a double spiral pinion on a transverse axis projecting in meshing engagement between said buttress gears, the working faces of the spiral pinion having a major spiral pitch and a minor helical pitch and adapted to exert power upon series of teeth on the converging arcs of the buttress gears substantially at right angles to the transverse axis, in combination with a gear on the middle of said double spiral pinion, and driving means meshing with said gear, the axis of said driving means lying substantially in the central plane normal to the transverse axis of the double spiral pinion.

3. A jack comprising a frame, a double rack-bar therein, pinions meshing the rack-bar at opposite sides, a pair of gears connected with the rack-pinions and having buttress teeth reversely disposed, a double spiral pinion on a transverse axis projecting in meshing engagement between said buttress gears, the working faces of the spiral pinion having a major spiral pitch and a minor helical pitch and adapted to exert power upon series of teeth on the converging arcs of the buttress gears substantially at right angles to the transverse axis, in combination with worm wheel teeth on the central periphery of the double spiral pinion clear of the buttress gears, and a central driving worm meshing with said teeth.

4. A jack comprising a stand, a double rack-bar therein, pinions meshing the rack-bar at opposite sides, a pair of gears connected with the rack-pinions and having 5 buttress teeth reversely disposed, a double spiral pinion on a transverse axis below said gears and projecting in meshing engagement between the same, the working faces of the spiral pinion having a major 10 spiral pitch and a minor helical pitch and adapted to exert power upward upon series of teeth on the converging arcs of the buttress gears, in combination with a gear on the middle of said double spiral pinion, and 15 driving means meshing with the lower part of said gear, the axis of said driving means lying at an upward inclination substantially in the central plane normal to the transverse axis of the double spiral pinion.

5. In a device of the character described, 20 the combination with a frame, a double rack-bar therein, pinions meshing the rack-bar at opposite sides, and a pair of gears connected with said rack-pinions, of a compound 25 pound gear member mounted on a transverse axis and projecting between said gears, said gear-member having lateral pinion portions meshing said gears and a central gear portion clear of the same, and 30 driving means meshing said central gear portion.

6. In a jack, the combination with a frame, a double rack-bar therein, pinions meshing the rack-bar at opposite sides, and 35 a pair of gears connected with said pinions, of bearings in the frame, a supporting shaft loose in said bearings, a compound gear-member loose on said shaft between said bearings and projecting between said 40 gears, said gear-member having lateral spiral pinion portions meshing with said gears and a central gear portion clear of

the same, and driving means meshing said central gear portion.

7. In a jack, the combination with a 45 frame, a double rack-bar therein, pinions meshing the rack-bar at opposite sides, and a pair of gears connected with said pinions, of bearings in the frame, a supporting shaft loose in said bearings, a compound gear-member loose on said shaft between said 50 bearings and projecting between said gears, said gear-member having lateral spiral pinion portions meshing with said gears and a central gear portion clear of the same, 55 driving means meshing said central gear portion, and a cover formed to retain the loose shaft against endwise displacement.

8. A jack, comprising a frame, a double rack-bar therein, said rack-bar having its 60 rack-teeth sides recessed, a pair of pinions engaging in said recessed sides, a pair of buttress gears united with said pinions, a double spiral pinion on a transverse axis 65 projecting in meshing relation between said buttress gears and having a central gear portion clear of the same, and a driving pinion meshing said central gear portion.

9. A jack, comprising a frame, a double rack-bar therein, said rack-bar having its 70 rack teeth sides recessed, a pair of shafts at opposite sides of the rack-bar, a pair of pinions on said shafts engaging in said recessed sides of the rack-bar, said pinions being composed of separate laminations keyed on 75 said shafts and confined by the recesses of the rack-bar, a pair of buttress gears on said shafts, a double spiral pinion on a transverse axis projecting in meshing relation between said buttress gears and having a central gear portion clear of the same, 80 and a driving pinion meshing said central gear portion.

JOHN C. KOPF.
